UNITED STATES PATENT OFFICE.

HENRY WIESNER, OF CHICAGO, ILLINOIS.

INTERNAL-COMBUSTION ENGINE.

1,369,511.

Specification of Letters Patent. Patented Feb. 22, 1921.

Application filed June 9, 1919. Serial No. 302,857.

To all whom it may concern:

Be it known that I, HENRY WIESNER, a citizen of Czechoslovakia, residing at Chicago, in the county of Cook and State of Illinois, have invented certain new and useful Improvements in Internal-Combustion Engines, of which the following is a specification.

The invention relates to internal combustion engines and a new and improved method of operating them and has for its object to utilize a large portion of the energy usually carried away by the exhaust gases of combustion and to reduce other heat losses and more particularly the heat that is dispersed by cooling water or by forcible drafts of air.

Other, further and more particular objects of my invention will become readily apparent, to persons skilled in the art, from a consideration of the following description when taken in conjunction with the drawings, wherein:—

Figure 1 is a central section of my improved multiple cylinder engine in which my method of procedure may be carried into effect.

Fig. 2 is a section taken on line 2—2 of Fig. 1.

Fig. 3 is a central vertical section of a modification.

In all the views the same reference characters are employed to indicate similar parts.

As the two stroke cycle engine offers greater advantage than the four cycle engine, providing a smaller number of cycles per impulse, it has been selected to show the proper arrangement of parts and the general construction of such an engine that is necessary to carry my mode of procedure into effect, although by changing somewhat the arrangement of the parts, as will readily appear to one skilled in the art, the method herein disclosed is equally applicable to engines of the four cycle type.

In carrying my invention into effect, I prefer to use three cylinders with as many reciprocating pistons, as clearly shown in Fig. 1, all of the pistons being connected to a common power-shaft and being of relatively appropriate size.

In this exemplification, cylinder 1 is used for compressing the charge which later, at

the end of the instroke, is transferred to cylinder 2, the piston of which at that time is also at the end of its instroke, because both pistons move in unison, as will be seen from their respective cranks being at the same angle, and on the same side of the axis of the shaft. The transfer of the compressed charge, from cylinder 1 to cylinder 2, is followed immediately by its ignition and the expanding gases in cylinder 2 are producing the power stroke. When piston 10, in cylinder 2, has traveled the first one-half of its power stroke, the remaining portion of the stroke will not so advantageously utilize the expanding gases of the charge, therefore I utilize the gases from this cylinder in another cylinder of preferably larger dimensions, and for this purpose the port 11 in the side of the cylinder 2 will be open, which leads to channel 12 forming a communication between cylinders 2 and the top of cylinder 3.

It will be observed that the cranks within cylinders 1 and 2 are coincident and in cylinders 2 and 3 they are at right angles to each other, being 90 degrees apart, the crank of cylinder 3 following the former immediately in the direction of motion. Therefore, when piston 10, in cylinder 2 is at its mid-stroke, the crank of cylinder 3 is at the end of its instroke. These respective positions are clearly shown in Fig. 1.

When in these positions the gases from cylinder 2, still under pressure, enter cylinder 3 and begin their expansible effect on the piston 13, which is preferably much larger in sectional area, thereby creating a second power stroke which is commencing about the time that the crank in cylinder 2 has progressed about midway of its power stroke. Thus two power strokes or impulses are available from one charge of burning gases in a given cycle, but if another set of three cylinders are applied to the same crank shaft, as may be done, four power strokes would thus be obtained in one revolution of the crank shaft by the use of an engine having six cylinders.

More specifically describing the structure shown, 4 is a carburetor, attached to the intake pipe 5, and when piston 6 in cylinder 1 is starting on its out or suction stroke, the suction valve 7 is open by means of a push rod operated from the cam shaft which in

the structure shown in Fig. 1 turns at the same speed as the crank shaft. Of course this valve may be operated direct from the power shaft, or it may open by reason of attenuation within cylinder 1.

Valve 7 is kept open during the entire out stroke and will be closed after piston 6 has started on its instroke or compression stroke.

A delivery valve 20 in the cylinder head 10 of the cylinder 1, controls the passage of the highly compressed charge into the cylinder 2. For this purpose, a powerful spring 21, in the valve cover 22, keeps the valve closed until the desired pressure is reached, or until 15 a short time before the end of the instroke of the piston 6. The action of the valve 20 may be made automatic to open at a critical pressure by adjustment of the spring 21, but it may also be made to move positively at a 20 predetermined time by any convenient mechanical mechanism arranged for the purpose.

A small part of the residuary gases in cylinder 2, remaining from the previous combustion, will be compressed by the simultaneous upstroke of piston 10 and the compressed charge from cylinder 1 is now injected into the clearance within the combustion space of cylinder 2. The charge is immediately ignited by means of the spark plug 23, or by any other suitable igniting method, the pressure in cylinder 2 may be sufficiently high to ignite the charge spontaneously. The power stroke is now taking 30 place in the cylinder 2 and since the valve 20 is closed by the spring 21, the suction stroke is taking place in cylinder 1 by the outward movement of the piston 6.

When piston 10 is in a position shown 40 at the middle of its stroke, the port 11, in cylinder 2, is open and the gases of combustion from the cylinder 2 then flow through the channel 12 into the upper part of cylinder 3.

45 For a better understanding of the mode of operation, it might be well to consider here the last power stroke of cylinder 3. When piston 13, in cylinder 3, commenced its previous power stroke, piston 10, in cylinder 2, was at midstroke, and when piston 13 reaches midstroke, piston 10 is at the end of its outstroke. Immediately after piston 10 starts on its instroke, piston 13 is completing its outstroke and near the end 55 of the latter, the exhaust port 14 is opened, whereby all the gases are ejected and atmospheric pressure is established in the cylinder 3 and also in cylinder 2, since the port 11 at this time has not yet been closed. A little later, however, port 11 will be closed by the ascending piston 10 and a half cylinder full of gases of combustion will be trapped in cylinder 2. An outlet for a portion of these gases is provided by the valve 15, located in the cylinder head 16. The valve

will be kept open for a short time by the cam 17 on the counter or main shaft, as the case may be, and as shown in Fig. 2.

While the ingoing piston 10 is reaching midstroke, piston 13 commences its instroke. The exhaust port 14 will be closed and a portion of the burned products of combustion or gases in cylinder 3 will be scavenged out through the valve 18, which is opened, at a predetermined time, by the cam 19 on the cam shaft, so that about two thirds of the gases are forced out of the cylinder 3, while one-third of them remains. The incarcerated gases are compressed by the further instroke of the piston 13, which will 75 fill the clearance space above the piston and the channel 12 so that the pressure obtained therein will approximately equal that existing in the cylinder 2 at the time when the piston 10 is about to open the port 11. The compression of these gases into the clearance space of cylinder 3, and into the channel 12, is of greatest importance, in fact it is 80 essential to utilize efficiently the compound effect of the expanding gases from cylinder 2 because if no such counter-pressure prevails, part of the pressure of the gases from cylinder 2 would be uselessly expended by unnecessary expansion in the void spaces, without accomplishing any useful work. 85 Although some power must be employed for compressing these elastic gases in cylinder 3, this power will be regained by their following expansion due to their elastic qualities. Compression, however, is necessary in this case since the process of compounding gas engines is depending upon it, and can only be carried out efficiently when the gases, available for the purpose, are still 90 under high pressure, and when they are utilized in spaces containing a corresponding counter pressure. 100

In Fig. 3, 1 represents the cylinder in which the gases are compressed, 2 is the cylinder in which explosion takes place and 3 is the low pressure cylinder in which the products of combustion of a previous charge have been compressed and in which the exhaust gases from the cylinder 2 are admitted when the valve 15 is open, the heat of the 110 exhaust gases serving to expand the compressed gases in the cylinder 3 adding greatly to the power imparted to the piston 13.

In Fig. 3 the structure as shown may be 115 used for a four cycle engine in which event cylinder No. 1 will not be required.

The low pressure cylinder has the products of combustion of the previous charge entrapped and compressed therein, which gases 120 later on are heated and expanded by the waste gases of combustion of the main cylinder in which the explosion has taken place. An expansive force is thereby created in the low pressure cylinder which is greater than 125 130

that expanded for compressing the gases in said cylinder. The efficiency of the engine is increased and the power made greater by expanding the compressed gases in the low 5 compression cylinder by the heat of the exhaust gases from the main or smaller cylinder.

While I have herein shown one means by which my method of procedure may be carried 10 into execution and have described in some detail the construction of such a mechanism, it must be borne in mind that the method of procedure is not to be limited to the apparatus shown and described in every 15 essential, as considerable variation may be made therefrom without materially affecting the mode of operation.

I have shown, in the drawings, that pistons 6 and 10 are mounted upon cranks that 20 are in the same constant plane, whereas there might be some slight difference in their positions and still the invention may be carried into effect, and the relation of piston 13 need not be essentially as shown, as it is quite 25 evident that a larger diameter of this piston will utilize the fuel to a greater extent by the pressure that is imposed upon it.

The extended expansion of the gases in the second cylinder, from the one in which the 30 initial expansion has taken place, has the great advantage of prolonging the time period for the combustion to act advantageously upon the cranks during the power stroke, so that maximum effect of the burning 35 gases is maintained during, substantially, the entire continuance of about three-fourths of a revolution of the crank shaft.

Having described my invention, what I claim is:—

1. The method of operating internal combustion engines, which consists in compressing 40 a charge in a cylinder; transferring the charge, in a highly compressed condition, into the combustion space of the second cylinder when the piston thereof is near its in-stroke; compressing air and products of combustion in a third cylinder; igniting the mixture in the second cylinder and expanding the gas thereof into said third cylinder 45 when the piston thereof is about to begin its power stroke and when the piston of the second cylinder has completed a predetermined part of its power stroke.

2. The method of operating internal combustion engines, which consists in compressing 55 a charge in a cylinder; transferring the charge, in a highly compressed condition, into the combustion space of a second cylinder, when the piston thereof is near the end 60 of its in-stroke; igniting the mixture and expanding the resultant gas into a third cylinder in which a portion of the products of combustion of a previous charge has been compressed, when the piston thereof is about

to commence its power stroke and at a time 65 when the piston of the second cylinder has completed about one half of its power stroke.

3. The method of operating internal combustion engines which consists in compressing 70 a charge in a cylinder; transferring the charge, in a highly compressed condition, into the combustion space of a second cylinder, the piston of which has reached the substantial end of its in-stroke simultaneously 75 with the piston of the first cylinder; compressing products of combustion in said third cylinder; igniting the mixture in the second cylinder and expanding the resultant gases in a third cylinder at a time when the power stroke of the third cylinder is started 80 and the power stroke of the second cylinder is half completed.

4. The method of operating gas engines 85 which consists in expanding a charge in one cylinder and at substantially half stroke of the piston thereof, admitting the resultant gases into another cylinder in which the piston is just beginning its power stroke and in which gases from a previous explosion are 90 compressed.

5. The method of operating internal combustion engines which consists in igniting a charge in one cylinder and while the piston thereof is at mid-stroke, admitting a portion 95 of the gases into another cylinder containing compressed gases, the piston whereof is about to begin its power stroke.

6. The method of operating internal combustion engines which consists in igniting a 100 charge in one cylinder and while the piston thereof is at mid-stroke admitting a portion of the gases into another cylinder, of larger diameter containing compressed gases, the piston whereof is about to begin its power 105 stroke and completing the power stroke of the first piston at reduced pressure.

7. The method of operating internal combustion engines which consists in igniting a 110 charge in one cylinder, using the gases in said cylinder and in a second cylinder containing compressed gases of a prior explosion, the crank of which is at substantial right angles to the crank of the first cylinder and which immediately follows the first 115 crank, in direction of movement, so that the power impulse of the second cylinder supplements that of the first cylinder in a given revolution of the engine shaft.

8. The method of operating internal combustion engines which consists in igniting 120 a charge in one cylinder, using the gases in the said cylinder and in a second cylinder, in which the products of combustion of the former charge have been compressed to substantially equal the pressure of the subsequent charge, the crank of which is at substantial 125 right angles to the crank of the first

cylinder and which follows the first crank immediately in direction of movement, so that the power impulse of the second cylinder supplements that of the first cylinder.

- 5 9. The method of operating gas engines which consists in expanding a charge in one cylinder and at substantially half stroke thereof admitting the resulting gases into another cylinder containing compressed gases
10 of a previous explosion and in which the piston is just beginning its power stroke and maintaining the temperature of the charge during compression at a point just below that at which premature explosion will
15 ensue.

10. An internal combustion engine having in combinative association three cylinders, two of which are connected to cranks on the same side of the shaft axis and in
20 substantially the same horizontal plane, whereby to compress a charge in one cylinder; a valve, having a spring to close it, controlling communication between the first and second cylinder; a port between the
25 second and third cylinder opened when the piston of the second cylinder is at mid-stroke position and a third cylinder having a piston and a crank at right angles to the crank of the first and second cylinders and
30 immediately following in direction of motion.

11. The method of increasing the efficiency of an internal combustion engine which consists in expanding the gases in a cylinder by combustion; compressing products of combustion of a previous charge in a second cylinder and admitting the partly expanded gases of the first cylinder into the second cylinder with the compressed gases

after the piston of the first cylinder has 40 made a portion of its power stroke.

12. The method of increasing the efficiency of an internal combustion engine which consists in compressing a fuel charge in a cylinder; transferring the charge to a 45 second cylinder; expanding the gases in the second cylinder by combustion; compressing a part of the products of combustion of a previous charge in a third cylinder and admitting the partly expanded gases of the 50 second cylinder into the third cylinder with the compressed gases after the piston of the second cylinder has made a portion of its power stroke.

13. In an internal combustion engine the 55 combination of the main cylinder with an intake valve for the supply of fuel; a second cylinder connected with its piston to the same crank shaft as that of the first cylinder but disposed at 90 to 180 degrees therefrom; 60 a valve for controlling communication between the two cylinders; means for opening the said valve at a predetermined time for the passage of gases of combustion from the first cylinder into the second cylinder; an 65 exhaust valve in the latter; means to keep the said exhaust valve open during exhaust and suction stroke of the piston of said second cylinder and for keeping it closed during the next up stroke and during the 70 following down stroke whereby gases of combustion will be entrapped and compressed in the second cylinder and heated and expanded by the gases from the main cylinder. 75

In testimony whereof I hereunto subscribe my name.

HENRY WIESNER.
